UNITED STATES PATENT OFFICE.

JOHN A. MORRISON AND NOAH J. BECKNER, OF NORTH YAKIMA, WASHINGTON.

SWITCH-LOCK.

1,286,060.

Specification of Letters Patent. Patented Nov. 26, 1918.

Application filed June 6, 1918. Serial No. 238,540.

To all whom it may concern:

Be it known that we, JOHN A. MORRISON and NOAH J. BECKNER, citizens of the United States, residing at North Yakima, in the county of Yakima and State of Washington, have invented certain new and useful Improvements in Switch-Locks, of which the following is a specification.

This invention relates to railways, and 10 more especially to switch stands; and the object of the same is to produce an improved lock for the switch lever.

A further object is to produce means for 15 ejecting the lever from the lock when the bolt in the latter is retracted.

A yet further object of the invention is to provide means for releasing the key.

Other objects will appear in the following specification and claims, and reference 20 is made to the accompanying drawings, wherein:—

Figure 1 is a side elevation of this device complete.

Fig. 2 is an enlarged elevation of the device with the front plate of the casing removed,

Figs. 3 and 4 are vertical sections on the lines 3—3 and 4—4 respectively of Fig. 2,

Fig. 5 is a sectional detail on the line 5—5 30 of Fig. 2.

Fig. 6 is a front elevation showing the key-hole guard.

In the drawings the numeral 10 designates broadly a casing including front and 35 rear plates or walls 11 and 12, the latter formed with spaced and depending ears 13 and a hook 19 to engage the switch stand which we have not thought necessary to illustrate. The switch lever is shown at 16, 40 pierced with an eye or hole 17 in one end and pivoted at 15 for swinging movement as usual. When this lever is swung to pendant position, the perforated end thereof passes into a channel 18 within the casing or housing, this channel being formed 45 by two upright flanges 20 and 21 therein as best seen in Fig. 2, and these flanges have aligned openings through which passes the tip of a bolt 22, the bolt also between the 50 flanges passing through the eye 17 in the lever 16 and locking the same in a manner which will be clear. The bolt slides within a guide 23 within the casing as seen at the right of Fig. 2, and is provided through 55 its body with a pin 30 engaging a notch 29

in the lower end of a lever 27 which is pivoted at 28 and forked at its upper end as at 31, one fork-arm having an inturned hook 34 at its extremity. A spring 32 bearing against the lever 27 normally projects the 60 bolt across the channel.

For retracting said bolt peculiar mechanism is employed for swinging the lever 27 on its pivot 28, as will now be described. Into a key-hole 24 in the front wall 11 of 65 the casing is passed a key 25 which has a tubular shank moving over a rigid stud 26 projecting forward from the rear wall 12 and surrounded by a tube 35 spaced from the stud so as to produce an annular channel 36 between them. Into this channel slides the tubular stem of the key, while its bit 33 passes over the tube as perhaps best seen in Fig. 5. When the key is inserted its bit strikes a collar 37 which is slidably 70 mounted around the tube 35 and urged forward by a spring 38, so that its normal tendency is to eject the key when the bit of the latter stands opposite the slot forming part of the key-hole 24 as usual. Said collar 75 has a radial lip at one side as at 40 standing normally between two spaced lugs 41 on the casing, and slidably between them so that the collar may not rotate while the key may. At its other side said collar has 80 a hook 42 which engages behind the left hand fork-arm 31 when the collar is forward but disengages the same when the collar is moved and the spring 38 is compressed, the 85 hook 42 has disengaged the fork arm 31; then the key is turned so that its bit 33 swings around between the fork-arms as indicated by the arrow in Fig. 2, finally moving the entire fork to the left and coming up against the hook 34 to prevent its further turning movement. This swings the lever 27 on its pivot 28 and retracts the bolt 22 and the same will remain retracted so 90 long as the key is not moved. Reverse movement of the key is permissible until it passes the position shown in Fig. 2 and begins to ride up the inside of the right hand fork-arm, and during this movement it 95 swings the lever 27 in the opposite direction and forcibly projects the bolt 22. Therefore it is impossible to remove the key without shooting the bolt, because the key must 100 come around to a position opposite the slot- 105 110

ted portion of the key hole before it can be withdrawn. When it reaches this position, the expansive force of the spring 38 will compel the withdrawal or ejection of the key and the expansion of this spring moves the collar 37 forward so that the hook 42 reengages the left hand fork-arm 31 and the parts stand as seen in Fig. 2. The perforated end of the lever 16, or whatever element is to be engaged by the bolt 22, will pass through an opening in the rear wall 12 of the casing and into the channel 18 between the two flanges 20 and 21, and this perforation must come in alinement with the bolt as will be clear. Within this channel stands a swinging finger 50 pivoted at its upper end at 51 in one of the flanges 21 and having a lever 52 carried by its pivot and provided with an offstanding ear 53 to which is connected a contractile spring 54. The position of parts is such that the normal tendency of the spring is to swing the finger forward within the channel 18 which in reality is rearward within the casing or housing, with the result that it ejects the element which was previously locked therein. Also, for safety purposes we provide another spring 55 which may bear down on the ear 53 for the same purpose. Now when the element 16 moves into the casing as shown by the arrow in Fig. 3, the finger 50 is swung inward so that the holes through the two flanges 20 and 21 are exposed and the bolt 22 may be shot forward through the eye 17 in said element 16. Later, as the bolt is retracted, however, the force of the springs 54 and 55 swings the finger 50 in the opposite direction and ejects the element 16 from the casing as soon as the bolt 22 has been completely withdrawn from the eye 17. Thus it is hardly possible for the operator even accidentally to leave this device unlocked for as soon as it is unlocked the element 16 is thrown out of the lock casing and the operator would see it. Furthermore he cannot remove the key without locking the device, and if his key is on a ring or chain he cannot leave his post without securing the key. These considerations throw every element of safety around the structure and make it serviceable as a switch lock, and especially applicable to switches in important places or on trunk or through lines where it is imperative that no switchman shall leave the switch stand with the through line track open.

The foregoing description and the drawings have reference to what may be considered the preferred, or approved, form of our invention. It is to be understood that we may make such changes in construction and arrangement and combination of parts, materials, dimensions, et cetera, as may prove expedient and fall within the scope of the appended claims.

Having thus fully described our invention, what we claim as new and desire to secure by Letters Patent, is:—

1. In a lock for switch stands, the combination with a switch lever having an eye, 70 a casing having an interior channel into which the perforated end of the lever is adapted to pass, the walls of the channel having alined holes, and a bolt movable through said holes and the eye of the lever; 75 of key-operated mechanism for actuating the bolt, a finger pivoted at its upper end within the casing and hanging within said channel, a lever fast on the finger and having an outstanding ear, and a spring moving said 80 ear in a direction to swing the finger and normally eject the switch-lever, for the purpose set forth.

2. In a lock for switch stands, the combination with a switch lever having an eye, 85 a casing having an opening in its rear wall and an interior channel into which the perforated end of the lever is adapted to pass, the walls of the channel having alined holes and the casing having a guide opposite them, 90 and a bolt movable in said guide through said holes and the eye of the lever; of a pivoted lever connected at its lower end with said bolt and having a fork at its upper end, key-operated mechanism working within 95 said fork to swing the last-named lever and actuate the bolt, a finger pivoted at its upper end within the casing and hanging within said channel, a lever fast on the finger-pivot and having an outstanding ear, and a spring moving said ear in a direction to swing the finger and normally eject the switch lever, 100 for the purpose set forth.

3. In a lock for switch stands, the combination with a casing having an opening in 105 its rear wall, a pair of upright spaced flanges within the casing having alined holes, a transversely movable bolt registering with said holes, and key-actuated mechanism for retracting said bolt; of a finger movably 110 mounted between said flanges and having a pivot extending through one of them, a lever fast on said pivot, and a spring moving said lever in a direction to normally swing the finger forward and eject the element which 115 is locked by the projection of said bolt.

4. In a lock of the class described, the combination with a casing having a guide, a bolt moving therein, a pivoted lever connected at one end with said bolt and having 120 its other end forked, and a spring moving the lever normally in a direction to project the bolt; of a stud and a surrounding tube fast within the casing and defining an annular channel between them, the casing wall 125 having a key-hole opposite said channel and fork adapted for the insertion of a key which passes between the arms of said fork, and fork-locking mechanism slidably mounted on said tube and thrown out of engage- 130

ment with the fork by the insertion of the key.

5. In a lock of the class described, the combination with a casing having a guide, 5 a bolt moving therein, a pivoted lever connected at one end with said bolt and having its other end forked, and a spring moving the lever normally in a direction to project the lever normally in a direction to project the bolt; of a stud and a surrounding tube fast within the casing and defining an annular channel between them, the casing wall having a key-hole opposite said channel and 10 fork adapted for the insertion of a key which passes between the arms of said fork, a collar loosely encircling said tube, a hook on the collar to engage one fork-arm, a spring pressing the collar normally forward 15 and yielding when the key is inserted, a lip projecting radially from the collar, and a guide in the casing along which said lip slides.

10 20

6. In a lock of the class described, the combination with a casing having a guide, a bolt moving therein, a pivoted lever connected at one end with said bolt and having

its other end forked, and a spring moving 25 the lever normally in a direction to project the bolt; of a stud and a surrounding tube fast within the casing and defining an annular channel between them, the casing wall having a key-hole opposite said channel and 30 fork adapted for the insertion of a key which passes between the arms of said fork, a collar loosely encircling said tube, a hook on the collar to engage one fork-arm, a spring pressing the collar normally forward 35 and yielding when the key is inserted, a lip projecting radially from the collar, and a guide in the casing along which said lip slides.

In testimony whereof we hereunto affix 40 our signatures in the presence of two witnesses this 8 day of May A. D. 1918.

JOHN A. MORRISON.
NOAH J. BECKNER.
